UNITED STATES PATENT OFFICE.

UDO BAMBERGER, OF EBERSWALDE, NEAR BERLIN, GERMANY.

CRANE.

Application filed March 4, 1926, Serial No. 92,251, and in Germany March 7, 1925.

The invention relates to cranes of the kind having compensating mechanism for maintaining the load at a constant level during the luffing of the jib whereby the power required for raising and lowering the jib is kept down to a minimum, said mechanism including a sheave over which the load rope passes and which though movable is always situated to the rear of the jib pivot through the whole amplitude of movement of the jib.

In cranes of this kind it has been proposed to mount the compensating sheave on the end of a lever pivoted to a rigid triangulated framework fixed to the crane chassis, said lever being connected by means of a rod or cable to the jib so that on the luffing of the jib the lever is rocked, thus moving the sheave to compensate for the shortening or lengthening of the load rope, with the upward or downward movement of the jib.

The object of the present invention is to provide a more simple construction of the compensating mechanism notably by the avoidance of such parts as a fixed triangulated support with a pivoted lever, and rods or cables for rocking the same, but which is nevertheless quite efficient in operation.

Referring to the accompanying drawings: Figure 1 is a constructional form of the crane given by way of example.

Figure 2, is a diagram of a working operation in three positions.

The jib *a* is adapted to rotate round a pivot *o*. The cable coming from the head *b* of the jib runs over a sheave *c* and over a fixed roller *d* to the drum *e*. The sheave *c* is supported by means of two struts *f* and *g*, the strut *g* being mounted by means of a pivot *h* to the top for instance of a travelling cabin. The strut *f* is connected by means of a pivot *i* with the tail of the jib. The roller *c* runs upon an axis which simultaneously represents an articulated connection between the guide members *f* and *g*. The lower edge of the jib and of the guide member *g* are provided with counter-weights *k* and *k'*.

On pulling in the jib the head of the jib

passes from the position *b* (Figure 2) to the position *b'* and thence to the position *b''*. At the same time the sheave *c* moves from the position *c* shown in full lines to the position *c'* and thence to the position *c''*. Owing to this movement the length of the cable between the rollers *d*, *c* and *b* is shortened and consequently with the winding drum *e*, stationary the cable runs over the roller *b* in a downward direction, whereby the load is maintained in a horizontal plane as clearly indicated in Figure 1. The special rope guide affords the further advantage that the force acting upon the strut *f* and resulting from the stresses upon the cable gives rise to a torque or turning movement which is directed in opposition to that of the load and the natural weight of the jib. This effect is further augmented by means of the counterweight *k'* attached to the strut *g*.

What I claim and desire to secure by Letters Patent of the United States is:

1. In a luffing crane of the kind set forth, a compensating mechanism comprising two relatively movable struts pivoted together at one of their two extremities and a sheave mounted on said struts at their point of juncture, the other extremity of the first said struts being pivoted to the jib and movable with the luffing thereof, while the other extremity of the second of said struts is pivoted to a fixed point.

2. A luffing crane of the kind set forth, comprising a jib pivoted between its head and tail to the crane structure, means for luffing said jib, a counter-weight on said tail, a strut pivoted at one extremity to said tail and movable therewith, a second strut pivoted at one extremity to the other extremity of said first mentioned strut and its other extremity to a fixed point, said struts being thus relatively movable, a load rope sheave mounted at the point of juncture of the two struts, and a counter-weight on said second mentioned strut.

UDO BAMBERGER.
